UNITED STATES PATENT OFFICE.

JOHN A. RATHBONE, OF DETROIT, MICHIGAN, ASSIGNOR TO RATHBONE MACHINE COMPANY, OF CLEVELAND, OHIO, A CORPORATION OF OHIO.

MOLDING MACHINE.

Application filed October 19, 1925. Serial No. 63,409.

The invention relates to molding machines of that type particularly designed for forming multiple molds and provided with opposed patterns respectively above and below a mold flask. To secure a proper print of the upper pattern, it has been found necessary to impart a high velocity to the relatively moving parts, which with certain constructions has been accomplished by the use of compressed air. It is the object of the present invention to accomplish this result in a slow acting mechanism and to this end the invention consists in the construction as hereinafter set forth.

In the drawings;

Figure 1 is a sectional elevation of the molding machine embodying my invention;

Figure 2 is an end elevation thereof;

Figure 3 is a plan view of the trip mechanism;

Figure 4 is a view similar to Figure 1 showing a modified construction.

Figures 5 and 6 are views similar to Figures 1 and 2 showing another modification.

As shown in Figure 1 my improved molding machine comprises a suitable base A, which supports the lower pattern plate B and flask C, the latter being provided with a sand frame D mounted thereon. Above the base is the vertically movable ramming head E, which carries the upper pattern plate F and holds the same in registration with the lower pattern plate by bearings G slidably engageable with guide pins H projecting upward from the base. Above the head E is a cross head I which slidably engages guides J on the bearings G. This head I is provided with a housing K for a spring L, the lower end of which bears against the head E and the upper end against an abutment on the housing. A shank M secured to and projecting upward from the head E passes centrally through the spring L and an aperture in the housing K, being provided with a notch or bearing N for engaging a latch or detent O, which in one position of the parts holds the spring L under compression. The cross head I is preferably mounted on swinging links P pivotally secured at P' to the base and permitting of laterally moving the heads E and I out of the way when the flasks are placed on or removed from the bed. The links P have at their upper ends

bearings P² slidably engaging headed rods Q, which at their upper ends are attached to the cross head I. The lower ends of these rods are pivotally connected to links R connected to rock arms R' on a rock shaft R² 60 operated by a lever handle R³.

At the rear of the machine is arranged a trip mechanism for disengaging the latch or detent O from the notch N of the shank M. This consists of a vertically arranged 65 rock shaft S journaled in bearings S', S² on the housing K. At the upper end of this rock shaft is a rock arm S³, which has a pin S⁴ for bearing against the latch O, which latter is pivoted on the shaft S and 70 is normally held in engagement with the notch N by a spring S⁵. The lower end of the rock shaft S has a pin S⁶ engageable with a cam S⁷ on the bed A, the arrangement being such that in the downward movement of 75 the head I the cam S⁷ actuating the pin S⁶ will trip the latch O, disengaging the same from the notch N.

With the construction as described, the parts being in the position as shown in Figure 1, the heads E and I are adjacent to each other, the latch is in engagement with the notch N of the shank M and the spring L is under compression. Assuming that the flask C and sand frame D are in position and filled 80 with loose sand, the operator draws downward upon the lever handle R³. This, through the rock shaft R², rock arms R' and links R, will draw downward the rods Q, which in turn will draw downward the heads 85 I and E. During this movement the engagement of the bearings G with the pins H will hold the pattern plate F in exact registration with the pattern plate B, so that the former is in position to enter the sand frame D and 90 flask C. The downward movement of the head I will also carry down the rock shaft S and at a certain point in this movement the pin S⁶ engaging the cam S⁷ will rock the shaft S, disengaging the latch O from the 95 notch N. This will immediately release the spring L, which will drive the head E downward at greatly accelerated velocity and will thereby produce the proper compacting of the sand about the pattern. The further 100 downward movement of the lever R³ will continue to depress the head I, while the head E remains stationary, and this will again compress the spring L and will move the latch O into engagement with the notch 105 110 N.

N. Thus after the first impact produced by the accelerated movement of the head E, a further compression of the sand may be effected by the lever R³ which also compresses the spring and engages the latch. The lever arm may then be raised again, which will carry up together the heads E and I, permitting of the removal of the flask and the repetition of the cycle. It will be understood that the machine is provided with the usual means for vibrating the patterns while they are being withdrawn from the molds, which, however, forms no part of the present invention and is therefore not shown.

In the construction shown in Figure 4 the movable ramming head T is arranged beneath a fixed head U and is moved upward by a hydraulically operated piston V. To impart the requisite acceleration to the ram, a spring W is arranged within the piston of the ram V and the hollow shank T' telescopically engaging said piston. A latch X normally holds the members T' and V from relative movement with the spring under compression, said latch having an actuating arm X' with a pivoted dog X² at the free end thereof for engaging a fixed hook Y. The arrangement is such that when the piston V is moved upward by hydraulic pressure, the hook Y engaging the dog X² on the arm X' will release the catch X, permitting the spring to quickly throw the ram upward. Following this operation the continued upward movement of the piston V will again compress the spring and engage the latch, thereby effecting the final compression on the mold and restoring the parts to position for a succeeding operation.

With the modified construction shown in Figures 5 and 6 instead of automatically releasing the stored power during the movement of the ramming head this power is released by a manually operable device. Thus, as shown, the spring L' is held under compression by a latch member Y' which may be manually released by the operation of a lever Y². This enables the operator to release the stored force at any time desired and when thus released the mold flask will be moved quickly upward into engagement with the upper pattern.

What I claim as my invention is:

1. In a molding machine, the combination with relatively movable members for respectively holding a pattern and a mold flask, of actuating means for imparting to said members a slow, powerful relative movement, means for storing a portion of the power of said actuating means and means for releasing the stored power to accelerate the relative movement of said members.

2. In a molding machine, the combination with relatively movable members for re-

spectively holding a pattern and a mold flask, of actuating means for causing said members to approach each other with a slow, powerful movement, means for storing a portion of the power of each movement of said actuating means and means for releasing the stored power to accelerate the relative movement during a portion of the cycle.

3. In a molding machine the combination with relatively movable members for respectively holding a pattern and a mold flask, of a member for actuating one of said members towards the other with a slow, powerful movement, resilient means intermediate said actuating member and the member actuated thereby in which force may be stored by a relative movement of said members, means for locking said last mentioned members in a relative position where force is stored in said resilient member and means for releasing said locking means to liberate said stored force and to accelerate the relative movement of the members respectively holding said flask and pattern.

4. In a molding machine, the combination with relatively movable members for respectively holding a pattern and a mold flask, of a member for actuating one of said members towards the other with a slow, powerful movement, resiliently yieldable means intermediate said actuating member and the member actuated thereby in which force may be stored during the final compression of said pattern against the sand of the flask, means for locking said actuating member and the member actuated thereby to retain said stored force during the retraction of said first mentioned members from each other, and means for releasing said stored force to impart a quick initial movement between the pattern and flask in a succeeding cycle.

5. In a molding machine, the combination with a member for supporting a mold flask and a member for supporting a superposed pattern, of a member for actuating one of said members toward the other with a slow, powerful movement, resiliently yieldable means between said actuating member and the member actuated thereby in which force may be stored during the final compression of said pattern against the sand in the flask, means for locking said members to retain the stored force and means for releasing said stored force to impart a quick relative movement between the pattern and the sand.

6. In a molding machine, the combination with relatively movable members for respectively holding a pattern and a mold flask, of manually operable means for imparting a slow, powerful movement to one of said members toward the other, means

actuated by said manually operated means for storing power, means for retaining and releasing the stored power to accelerate the relative movement of said pattern and flask.

5 7. In a molding machine, the combination with relatively movable members for respectively holding a mold flask and a superposed pattern, of manually operable means for imparting a slow, powerful movement

10 to one of said members toward the other, resiliently yieldable means between the said manually operable means and the member actuated thereby in which force may be

stored during the final compression of the pattern against the sand, means for locking 15 said actuating member and member actuated thereby to retain said stored force during the retraction of said members from the other of the first mentioned members and means for releasing said locking means 20 and said stored force to accelerate the relative movement of the pattern and mold flask whereby the sand will be compacted against the pattern by inertia.

In testimony whereof I affix my signature.
JOHN A. RATHBONE.
